United States Patent Office

Des. 234,055
Patented Jan. 7, 1975

234,055

TELEPHONE MESSAGE STAND

William J. Woods, 334 Aviador Ave.,
Millbrae, Calif. 94030

Filed Mar. 2, 1973, Ser. No. 337,288

Term of patent 14 years

Int. Cl. D14—03

U.S. Cl. D26—14 A

FIG. 1 is a front perspective view of a telephone message stand showing my new design;

FIG. 2 is a front elevation thereof;

FIG. 3 is a side elevation thereof;

FIG. 4 is a top plan view thereof; and

FIG. 5 is a rear elevation thereof.

The broken lines are shown for illustrative purposes only.

I claim:

The ornamental design for a telephone message stand, as shown and described.
